UNITED STATES PATENT OFFICE.

RILEY A. SHERWOOD, OF BILLINGS, MONTANA.

FISH-SCREEN.

1,143,147.

Specification of Letters Patent. Patented June 15, 1915.

Application filed April 21, 1914. Serial No. 833,509.

To all whom it may concern:

Be it known that I, RILEY A. SHERWOOD, citizen of the United States, residing at Billings, in the county of Yellowstone and State of Montana, have invented certain new and useful Improvements in Fish-Screens, of which the following is a specification.

This invention relates to fish screens of that general class especially designed for use in irrigating ditches, canals, flumes, and the like to prevent the fish from following the course of the stream and eventually becoming stranded on the land.

The object of the invention is to provide a revolving screen, which, when positioned in a ditch, flume, or other water course will afford an effectual barrier to the passage of fish without liability of becoming clogged or otherwise obstructed by leaves, twigs and other floating debris.

A further object of the invention is to provide a revolving screen having a water wheel associated therewith and operatively connected with the screen whereby rotation of the water wheel in one direction will cause a corresponding rotation of the screen in a direction transverse thereto.

A still further object of the invention is to generally improve this class of devices so as to increase their utility, durability and efficiency.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is a top plan view of a screen device constructed in accordance with the present invention; Fig. 2 is a central cross sectional view of the device; Fig. 3 is a front elevation, partly broken away; and Fig. 4 is an enlarged section on the line 4-4 of Fig. 1.

Referring now to the drawings by numerals, 1 designates a shaft, the extremities of which are journaled within bearings 2

embedded or attached in any suitable manner to concrete blocks or posts 3 disposed one each upon the respective banks of the stream or water course within which the screen is built. Water or paddle wheels 4 are mounted upon the said shaft 1, preferably in spaced relation and rigid therewith, said wheels, by reason of their disposition with respect to the passing stream, being rotatable to drive said shaft 1.

A suitable frame, designated as an entirety by the numeral 5 is positioned to extend parallel with the shaft 1, and slightly in advance of the paddle wheels 4, the respective ends of the said frame being permanently attached as at 6 to concrete blocks or posts 7 arranged upon each bank of the stream. A second shaft 8 is journaled within hanger bearings 9 depending from the said frame 5, said shaft extending parallel with the shaft 1, motion being imparted thereto through the medium of a sprocket chain 10 operating over wheels 11 and 12 mounted, one upon each of the said shafts 1 and 8. At each end of the said shaft 8 is mounted a beveled gear 13 meshing into a like gear 14 mounted upon a stud shaft 15 journaled within the said frame 5, its axis of rotation being at right angles to the axis of rotation of the said shaft 8. The said stud shaft 15 carries a sprocket 16 over which operates a chain 17, said chain also operating over a second sprocket 18 upon a vertical shaft 19 and a third sprocket 20 mounted upon a second vertical shaft 21. As is apparent upon reference to the drawings, the arrangement of the elements above described is in duplicate at the respective terminals of the frame 5.

A cylindrical frame or drum 22 is rotatable with and upon each shaft 19 and, as the said shafts 19 are positioned, one adjacent each of the respective banks of the stream, it is apparent that the screen 23 which operates thereover, may be made to travel or operate in a direction transverse to the direction of rotation of the paddle wheels 4. Both the shaft 19 and the shaft 20 are journaled at one end in the frame 5, their opposite ends being journaled within bearings 24 embedded within concrete blocks 25 seated or sunk into the bed of the stream. Each shaft 20 carries a revolving brush 26, so positioned with respect to the screen 23 as to engage the exterior surface thereof, the

said brush being of a length sufficient to engage the screen from one to the other of its opposite longitudinal edges.

A third vertically disposed shaft 27 is journaled at one end within the frame 5 and at its opposite end within a suitable bearing 28 positioned in the bed of the stream, the said shaft being disposed forwardly of the screen 23 and rotated by means of a chain 29 operating over sprockets 30 and 31 mounted respectively upon one of the shafts 19 and the shaft 27. About midway the length of the shaft 27, a suitable distance below the water line of the passing stream, is mounted a revolving wheel member 32, said member being of novel and peculiar construction whereby to represent moving fish.

By the above construction and arrangement of parts, it is apparent that the fish in attempting to follow the course of the stream, will be prevented from doing so by the revolving screen 23, the latter operating transversely of the stream and extending from one to the other of its banks; that the member 32 by reason of its arrangement forwardly of the screen 23 will, when rotating, tend to act as a guide whereby the fish will be directed away from the screen; and that the rotation of both the screen and the member 32, that is, the power necessary for such rotation, is derived solely by the impact of the passing stream against the blade of the paddle wheels 4.

In reduction to practice, I have found that the form of my invention, illustrated in the drawings and referred to in the above description, as the preferred embodiment, is the most efficient and practical; yet realizing that the conditions concurrent with the adoption of my device will necessarily vary,

I desire to emphasize the fact that various minor changes in details of construction, proportion and arrangement of parts may be resorted to, when required, without sacrificing any of the advantages of my invention, as defined in the appended claims. 45

Having thus fully described my invention, what I claim as new and desire to secure by Letters Patent, is:—

1. In a fish screen, a revolving screen member operating transversely of the water-way within which the screen is arranged, a rotary brush member operating against one face of the screen, a driven element, a single element engaging the driven element, said single element operating to rotate the screen and the rotary brush in opposite directions, and a rotary device operating in advance of the screen to scare approaching fish away, 60 said device being operable by said driven element, as and for the purpose set forth. 55

2. In a fish screen, a frame, a pair of shafts journaled within said frame, one shaft being disposed adjacent each of the respective banks of said stream, a drum upon each shaft, an endless screen member operating over said drums to form a barrier across the said screen, revolving brush members operating to clean said screen, a rotary member disposed forwardly of the said screen and beneath the water line of the stream, a water wheel, and means connecting said water wheel with the drums, the brush members and the rotary member for rotating the latter according to the rotation of said wheel. 75

In testimony whereof I affix my signature in presence of two witnesses.

RILEY A. SHERWOOD.
